The ornamental design for a steam bar for dry cleaning machine, as shown and described.

DESCRIPTION

FIG. 1 is a perspective view of a steam bar for dry cleaning machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof where the bottom plan view is a mirror image;

FIG. 7 is a perspective view thereof showing the state in which the steam bars have been installed in the dry cleaning machine; and,

FIG. 8 is an enlarged view of a part of the inside part of the steam bar in order to show the holes from which steam has been emitted.

The broken line showing of details in FIG. 7 is included for the purpose of showing environmental portions of the steam bar for dry cleaning machine and forms no part of the claimed design.
